UNITED STATES PATENT OFFICE.

JOHN C. CASSIDY, OF ST. LOUIS, MISSOURI.

GARMENT-SUPPORTER.

1,285,035.

Specification of Letters Patent. Patented Nov. 19, 1918.

Application filed August 13, 1917. Serial No. 185,820.

To all whom it may concern:

Be it known that I, JOHN C. CASSIDY, a citizen of the United States, residing at St. Louis, Missouri, have invented new and useful Improvements in Garment-Supporters, of which the following is a specification.

This invention relates to garment supporters and more particularly to a device for holding trousers up and preventing the shirt from creeping out at the waist. It has for its object to produce a simple and efficient structure which obviates the necessity for wearing a tight belt, or any belt at all, and which is yieldable to the movement of the body so as to prevent binding and tearing of the garments and avoid discomfort to the wearer.

The invention consists in the parts and in the combinations and arrangements of parts hereinafter described and claimed.

In the accompanying drawing forming part of this specification and wherein like characters refer to like parts wherever they occur in the several views,—

25 Figure 1 is a view illustrating how the device is worn;

Fig. 2 is a perspective view, on an enlarged scale, illustrating a practical embodiment of the invention;

30 Fig. 3 is a cross-section through the shirt-engaging buckle, showing how the slide-bar is mounted;

Fig. 4 is a fragmentary vertical section showing how the shirt is engaged in the buckle;

35 Figs. 5 and 6 are fragmentary detail views illustrating one form of the means for fastening the device to the waist-band of the trousers; and

40 Figs. 7 and 8 are fragmentary views illustrating a modification of the means for fastening the device to the waist-band.

In its preferred form the device comprises a branched supporting member, either substantially T-shape or Y-shape, but more preferably the latter, at the ends of whose arms 1 and 2 are angular extensions 3 and 4, respectively.

As shown in Figs. 2 and 5 the extensions 3 and 4 are turned outward, as at 5, and downward, as at 6, at their ends, and spring tongues 7 are secured to the arms 1 and 2 so as to normally bear with their serrated edge portions 8 against said downturned portions 6.

Secured to the stem portion 9 of the sup-

porting member, as by springs 10, is a slide-buckle 11. This slide-buckle preferably comprises parallel side-bars 12 and substantially V-shape cross-bars 13 and 14 at the ends 60 thereof. Mounted on the side-bars 12, as by bending its end portions about said side-bars, as shown more clearly in Fig. 3, is a slide-bar 15 which has the same form as the cross-bars 13 and 14, the formation of the 65 end portions 16 of the slide-bar being such that the body of the same is flush with the side-bars 12 and cross-bars 13 and 14. In this way the slide-bar 15 is free to move between the cross-bars 13 and 14, but is prevented from sliding off the buckle frame.

The supporting member is preferably made of pliable-metal, for example, semi-hard aluminum, which may be bent to conform to the wearer's waist and hip contour, 75 and yet is stiff enough to retain its shape when so conformed. In the use of the device it is inserted inside the trousers, as shown by dotted lines in Fig. 1, the portions 5 and 6 overhanging the waist-band, which latter 80 is engaged by the serrated edge portions 8 of the spring tongues 7 on the inner side, and thereby securely held in place. The lower portion of the shirt below the waist line is gathered and taken in a loop, first 85 outward through the opening between the cross-bar 14 and the slide-bar 15 of the buckle, and thence upward and inward through the opening between the slide-bar 15 and the cross-bar 13, as shown in Fig. 4, 90 after which the slide-bar is moved up close to the cross-bar 13. The shirt is thus securely engaged in the buckle, and most effectively so, owing to the peculiar shape of the cross-bars and the slide-bar.

95 In adjusting the device the shirt is engaged with the buckle with the side seam coinciding with the apex of the cross-bar 13, and the supporting member is adjusted on the waist-band so that the crotch 17 of the 100 arms 1 and 2 coincides with the side seam of the trousers. It is, therefore, noted that the peculiar formation of the supporting member and the shirt-engaging buckle is materially advantageous in facilitating the 105 proper positioning of the device.

The supporting member is also preferably formed so that, when it is applied as above described, the stem portion 9 inclines with its lower end slightly forward of the 110 side seam of the trousers, and its correlation to the buckle is such that the pull on the

garments is normally in line with the side seams of both of them, thereby affording comfort to the wearer, the springs 10 yielding to the movement of the body with equalizing effect and preventing the binding and tearing of the garments and at the same time holding the trousers up and preventing the shirt from creeping out.

If desired a single spring may be used instead of two as shown, in which case it will be attached at the middle of the stem 9 of the supporting member and middle of the cross-bar 14 of the buckle. So, too, instead of employing the spring tongues 7 for engaging the waist-band of the trousers, the extensions 3 and 4 of the arms 1 and 2 of the supporting member may be without the rebent end portions 5 and 6, but oppositely slotted, as at 18 (see Figs. 7 and 8), for engagement with buttons 19 or the like which are secured on the inner side of the waist-band.

Obviously, the devices are provided in pairs, rights and lefts, and they admit of considerable modification other than herein pointed out, without departing from the spirit of the invention as defined by the appended claims, and, therefore, are not limited to the exact construction herein shown.

30. What is claimed is:

1. In a device of the character described, a supporting member having a stem portion extending downward inside the trousers over the hip and oppositely disposed branches secured at their ends to the waist-band of the trousers on opposite sides of the side seam, a buckle secured to the shirt below the waist line, and resilient means connecting said buckle and the lower portion of the 40 stem of said supporting member, whereby the trousers are normally held up and the shirt down with their side seams substantially in line.

2. In a device of the character described, a pliable supporting member conformable to the contour of the wearer at the waist and hip, said member having means for engagement with the waist-band of the trousers on opposite sides of the side seam and projecting downward inside the trousers over the 50 hip, a shirt-engaging buckle having means

for locating the side seam of the shirt when applied, and a yieldable connection between said buckle and the lower portion of said supporting member.

55

3. In a device of the character described, a supporting member conformable to the contour of the wearer at the waist and hip, said member being substantially Y-shape and having means at the ends of its arms for engagement with the waist-band of the trousers, the stem of said member extending downward inside the trousers with the crotch of the arms of said member coinciding with the side seam of the trousers, a shirt-engaging buckle having means for locating the side seam of the shirt when applied, and a resilient connection between said buckle and the lower portion of said stem of the supporting member, whereby the trousers are normally held up and the shirt down with their side seams substantially in line.

60

4. In a device of the character described, a supporting member conformable to the contour of the wearer at the waist and hip, said member being substantially Y-shape and having means at the ends of its arms for engagement with the waist-band of the trousers, the stem of said member extending downward inside the trousers with the crotch of the arms of said member coinciding with the side seam of the trousers and the lower end of said stem projecting slightly forward of the side seam, a shirt-engaging buckle having substantially V-shape cross-bars and a correspondingly shaped slide-bar, the apexes of said cross-bars and slide-bar being upward when the buckle is applied, and a pair of springs connecting the lower end portion of the stem of said supporting member with the lower corners of said buckle, said springs yieldably holding said buckle in normal correlation to the crotch of the arms of said supporting member, whereby the trousers are held up and the shirt down with their side seams substantially in line.

70

In testimony whereof, I have hereunto set my hand at St. Louis, Missouri, this 8th day of August, 1917.

JOHN C. CASSIDY.
